UNITED STATES PATENT OFFICE.

BION H. MILLER, OF BAY CITY, MICHIGAN.

SAW-SWAGE.

SPECIFICATION forming part of Letters Patent No. 351,520, dated October 26, 1886.

Application filed September 24, 1884. Serial No. 143,861. (No model.)

To all whom it may concern:

Be it known that I, BION H. MILLER, of Bay City, in the county of Bay and State of Michigan, have invented new and useful Improvements in Saw-Swages; and I do hereby declare that the following is a full, clear, and exact description thereof, reference being had to the accompanying drawings, which form a part of this specification.

10 This invention relates to an improvement in saw-swages for circular saws; and the invention consists in the peculiar construction of the clamping-screws, as hereinafter described, and specifically set forth in the claim.

15 In the drawings which accompany this specification, Figure 1 is a vertical central section showing how the swage is used in operation. Fig. 2 is a cross-section thereof on line X X in Fig. 1.

20 A is the stock. It is provided upon its lower part with the central groove or recess, a, of sufficient width to enable it to straddle the saw-blade, as shown in the drawings.

B is the stationary die or anvil, removably 25 secured at the bottom of the recess a in any suitable manner.

C is the movable die, which is fitted into a corresponding slot, b, in the die-stock, so as to be firmly guided in its operation. Its upper 30 end is connected to a lever, D, the lower end of which terminates in an eccentric-head, c, which when the lever is vibrated reciprocatingly operates the movable die. The lower end of this movable die is provided with a 35 rounded shoulder, d, which operates against the face of the anvil, near the inner edge thereof.

E and E' are two clamp-screws tapped through the sides of the die-stock, with their 40 inner ends projecting within the groove a. One of these clamp-screws is provided with a hand-lever, F, for operating it. The object of these clamp-screws is to firmly clamp the tool to the saw-tooth under operation, the clamp-screw E' being at first sufficiently adjusted, so 45 that only a fraction of a turn of the other clamp-screw is required to firmly grip the tooth between them. To give a very firm hold, the inner faces of these clamp-screws are preferably 50 serrated. They are also so reduced in shape that if the tooth should be an inserted one

they will only grip the tooth proper and no part of the body of the saw, and in this lies the gist of my invention.

In practice, the tool is made to straddle the saw-tooth which it is desired to operate upon, bringing the cutting-edge of the tooth in proper position between the coacting parts of the dies. In this position the tool is held in place by the face of the anvil resting against the whole outer 60 face of the saw-tooth, and in this position the operator firmly clamps his tool to the saw-tooth by turning the lever F in the proper direction. The operation of swaging the tooth is then performed by the operator actuating 65 the lever D in the proper direction to force the shoulder d of the movable die against the saw-tooth. In this operation it first draws the metal from the base of the tooth toward its cutting-edge, compressing the metal and 70 spreading its cutting-edge, and then nipping off the waste at the cutting-edge.

To better steady the tool while in operation, I make the levers D F preferably move in opposite directions, so that the operator may 75 keep one hand upon the clamping-lever F while he is operating the other lever, D, using the former lever as a point of resistance, which allows him to use his utmost strength without danger of the clamp-screws gripping insufficiently tight. By reducing the ends of the clamp-screws, as shown, I not only provide 80 for the better swaging of an inserted tooth, but I am enabled to clamp the tooth right at the point where the swaging is being done. 85

I have shown and described the two levers for operating the movable die and the clamping device as being moved in opposite directions; but no broad claim is made to that construction in this case, as it forms the basis of 90 a claim in an application filed by me August 20, 1882, Serial No. 141,036.

What I claim as my invention is—

In a saw-swaging device, the clamp-screws E E', tapped through the sides of the stock, 95 and having reduced inner ends, substantially as and for the purposes specified.

BION H. MILLER.
